UNITED STATES PATENT OFFICE.

FRANK W. BARKER, OF BELMONT, NEW HAMPSHIRE.

CRADLE.

SPECIFICATION forming part of Letters Patent No. 257,459, dated May 9, 1882.

Application filed March 20, 1882. (No model.)

To all whom it may concern:

Be it known that I, FRANK W. BARKER, of Belmont, of the county of Belknap and State New Hampshire, have invented a new and useful Improvement in Cradles; and I do hereby declare the same to be described in the following specification and represented in the accompanying drawings, of which—

Figure 1 is a front elevation, and Fig. 2 a vertical and transverse section, of a cradle, provided with my invention, the nature of which is defined in the claim hereinafter presented.

In such drawings, A denotes the crib of the cradle, and B its supporting-stand, the two being constructed and arranged as represented or in any other suitable manner. Extending down from the crown of the arch a of the stand is a spiral spring, C, which, at its lower end, is jointed to the inner ends of two curved levers, D D, arranged in the stand and having their longer arms connected with the crib at its opposite ends, as shown. Each of said levers has extended from it an eye, b, to receive one of two hooks, c c, projecting from the arch of the stand.

If desirable, each of the curved levers may

be constructed of wire twisted into proper form, as shown, in which case such levers will be more or less elastic.

When the levers are in engagement with the hooks the crib may be swung laterally with a pendulous movement, and thus will be supported by the spiral spring, which will be contracted lengthwise by the weight of the crib. In this way the crib will have an elastic support, even while the levers are in connection with the hooks. On the levers being unhooked from the hooks they will be supported by the spring alone, in which case a child, when in the crib, can impart to it pleasurable vertical reciprocating movements.

I claim—

In combination with the crib A and its supporting-stand B, the spring C and the hooks c c and the two levers D D, provided with eyes b b, all being applied and arranged substantially in manner and to operate as set forth.

FRANK W. BARKER.
